UNITED STATES PATENT OFFICE.

ABEL T. NEWBURY, OF VERMILION, ALBERTA, CANADA.

FLYING-MACHINE.

990,897.

Specification of Letters Patent.

Patented May 2, 1911.

Application filed October 7, 1909. Serial No. 521,515.

To all whom it may concern:

Be it known that I, ABEL T. NEWBURY, a subject of the King of Great Britain, residing at Vermilion, Province of Alberta, Canada, have invented certain new and useful Improvements in Flying-Machines, of which the following is a specification.

My invention relates to certain new and useful improvements in flying machines, and 10 the object of my invention is to combine in one machine of this character the principles of the balloon, helicopters and aeroplanes, whereby a construction having great lifting power is produced.

15 With these objects in view my invention consists in certain constructions, combinations and arrangements of parts the preferred form of which will be first described in connection with the accompanying drawings and then the invention particularly pointed out in the appended claims.

20 Referring to the drawings wherein the same part is designated by the same reference numeral wherever it occurs, Figure 1 is a perspective view of a flying machine embodying my invention; Fig. 2 is a central longitudinal section thereof.

3 designates a gas container which is 25 formed of metal and is composed of an upper deck 4, a bottom portion 5 and sides 6, these parts being strengthened and stiffened by means of the cross ribs 7, 7. The front 8 of this container is inclined, as is best shown in Fig. 2, to form a lifting plane, and the 30 rear is closed by a plate 9. Interiorly the parts are strengthened by means of the cords 10 which tie the upper and lower plates 4 and 5 together, whereby the plates are prevented from bulging under the gas pressure 35 contained in said structure. As the gas pressure within the container varies with the atmospheric pressure, it is necessary to provide an expansion chamber in order to accommodate the gas when the same expands in the container 3. The construction 40 shown consists of a balloon structure 11 supported by means of the netting 12, below the container 3 and connected to the container by the tube 13.

45 14 is the passenger carrying car which is supported below the container 3 and the balloon bag 11 by means of the cords 15. As shown, this car is rectangular in form with its bow 16 inclined, in order to provide a 50 lifting plane.

55 Mounted at the four corners of the upper

deck 4 or the container 3 are the brackets 17 in each of which is journaled a vertical shaft 18, carrying at its lower end a helicopter 19. These helicopters are arranged so that when 60 driven they will assist in lifting the machine or lower it by reversing. As a means for driving these helicopters I provide each shaft 18 with a pulley 20, and running around all the pulleys is a belt 21 driven by 65 the engine 29 by means of the pulley 28 on the drive shaft of the engine engaging said belt.

In order to propel the machine forward 70 I provide propellers 24 at the rear of the container 3, these propellers being shown as carried on shafts 25 mounted in suitable bearings 26 supported on the main deck 4. These shafts 25 are driven by means of the belts 27 which extend from the long pulley 23 on the drive shaft of an engine 22 to each of the shafts 25. In order to further increase the driving power and to cause the car 14 to remain in substantially the same vertical plane as the container 3, I provide 80 said car with a driving propeller 30 at the stern thereof, said propeller being carried upon a shaft 31 of an engine 32. It is to be understood that while the engines 22, 29 and 32 are preferably gas engines, other forms 85 of engines may be used if desired.

From the foregoing description it will be obvious that I have provided a flying machine having great lifting capacity, due both to the power of the gas contained in the part 90 3, the helicopters, and the forward surfaces of the part 3 and the car 14. It is to be understood of course that suitable steering rudders are to be provided, but as they form no part of my invention I have not illustrated the same.

I realize that considerable variation is possible in the details of construction and arrangement of parts without departing from the spirit of my invention, and I therefore do not intend to limit myself to the specific form shown and described.

Having thus described my invention what I claim as new and desire to secure by Letters Patent is:

1. A flying machine comprising a metallic gas container of generally rectangular form having its forward end upwardly inclined to form a lifting plane, helicopters mounted on each corner of the container, driving means mounted on top of the container and connected to the helicopters, means mounted

upon the top of the container for driving the same forward, a car hung below the container and having its forward surface upwardly inclined to form a lifting plane, and 5 additional propelling means mounted in the car.

2. A flying machine comprising a metallic gas container of generally rectangular form, cords connecting the upper and lower portions of the container to brace the same against internal pressure, a gas bag below the container, an open connection between the gas bag and container, a car supported below the gas bag, propellers mounted upon 10 top of the container and also in the car, and means for driving each of said propellers. 15

3. A flying machine comprising a metallic gas container of generally rectangular form, helicopters mounted on each corner of the container, driving means mounted upon the top of the container and connected to the helicopters, propellers mounted upon the top of the container, means for driving the same, a car hung below the container, a propeller on the car and means in the car for driving 20 the propeller. 25

In testimony whereof I affix my signature in presence of two witnesses.

ABEL T. NEWBURY.

Witnesses:

W.M. F. ELLIS,
I. MYRTLE CLAY.
